UNITED STATES PATENT OFFICE.

EDWARD L. BISHOP, OF ATLANTA, GEORGIA.

MAIL-BOX LOCK AND COLLECTION INDICATOR.

Application filed October 16, 1922. Serial No. 594,968.

To all whom it may concern:

Be it known that I, EDWARD L. BISHOP, a citizen of the United States, residing at Atlanta, in the county of Fulton and State 5 of Georgia, have invented new and useful Improvements in Mail-Box Locks and Collection Indicators, of which the following is a specification.

This invention has reference to a combination lock and indicator for mail boxes and more particularly to a novel indicator mechanism for setting the hour of collection.

An important object of the invention is to provide a combination lock and collection 15 indicator of the character above specified which is key-actuated and which is so constructed as to be operable for indicating the hour of the next collection, only when the proper key is inserted in the lock.

20 An additional object of the invention is to provide a combination lock and mail-collection indicator of generally improved construction and design, and one which is adapted for both day and night collections, 25 novel means being provided for indicating A. M. and P. M. collections.

With these and other objects in view, which will become apparent as the description proceeds, the invention resides in the 30 construction, combination, and arrangement of parts, hereinafter more fully described and claimed, and illustrated in the accompanying drawings, in which like characters of references indicate like parts throughout 35 the several figures, of which:

Figure 1 is a side view of a mail box with a part broken away to disclose the combination lock and indicator;

Figure 2, an end view of the mail box 40 closing the indicator dial and key slot;

Figure 3, a vertical central section taken longitudinally through the lock and indicator mechanism;

Figure 4, a top view of the mechanism, 45 with parts shown in section, including a fragment of the key;

Figure 5, a detailed view of the dial catch, including the units associated therewith, and

50 Figure 6, a detailed view of the slide bar and pinion.

Fig. 7, a fragmentary view of the dial and lock, illustrating the A. M. and P. M. collection-indicating means.

Describing the invention in detail, 55 indicates a mail box of conventional type having the usual letter-drop 11 provided in one

side thereof and a hinged door 12 at one end. In applying the invention to the mail box, the door 12 is provided with a central opening to permit passage of the barrel 13 of 60 the lock mechanism, the same extending inwardly of the mail box and being provided with a circular head 14 suitably fastened to the door 12 by bolts, rivets, or other suitable fasteners 15. Head 14 is shouldered, as at 65 16, to provide a seat for a dial ring 17, the same being thus snugly engaged between the head 14 and the adjacent face of door 12, and being rotatable on its seat.

Extending longitudinally of the lock barrel 13 is a key-hole slot 18 which terminates inwardly of the inner end of the barrel, in a large circular recess 19. Located in recess 19 is the pinion 20 shown in Figure 6. This pinion is provided adjacent one edge with 70 teeth 21 for engaging the teeth 22 of slide bar 23, as hereinafter explained. At its opposite edge the pinion is provided with spaced peripheral grooves 24 with which engage lugs or ribs 25 formed on the inner 75 wall of recess 19. These ribs prevent end-wise movement of the pinion although permitting the same to freely revolve. The pinion is revolved by means of a key of conventional type (not shown), the tongue of 80 which is received in the key slot 28 of the pinion. The open end of recess 19 is normally closed by plug 29 threadedly engaged in the end of the lock barrel as illustrated.

Slide bar 23 is employed to lock door 12 90 to the mail box and is provided with a latch portion 30 resting flatly against the upper edge of the door and being slidably disposed through a guide bracket 31 fastened to the door as shown at 32. From a point below 95 the bracket, the slide bar extends rearwardly and downwardly as shown, terminating at its inner end in a depending rack portion 33 arranged in parallelism with latch 30 and being slidably disposed within the vertical 100 slot 34 of a guide casing 13' formed integral with one side of lock barrel 13 and communicating with recess 19 so that pinion 21 will mesh with the teeth 22 of rack bar 33. It will thus be seen that the pinion when 105 rotated by the turning of the key will raise or lower the slide bar, thus locking or releasing door 12, as will be readily understood from Figures 1 and 2.

To provide for indicating the hour of 110 collection, dial ring 17 is provided on its outer face with graduation and markings

similar to the graduation and markings of a clock dial. The dial ring is, moreover, provided around its central opening with a plurality of teeth 34'. Mounted on lock 5 barrel 13 for engagement with teeth 34' is a dial catch comprising a bar 35 pivotally supported in a saddle 36 suitably fastened to the lock barrel which it straddles as shown in the drawings. At one end catch 10 bar 35 is provided with an upstanding finger 37 which is suitably accommodated in a slot or other opening in the back of head 14 and pointed at its upper end for engagement with teeth 34' of the dial ring. The 15 catch is normally held in locking engagement with the dial ring to prevent rotation thereof, by means of a spring 38 and a plunger 39 arranged, as shown in Figure 3, to exert an upward thrust against the forward 20 end of the dial catch. The butt end 40 of the dial catch rests upon the upper edge of stem 41, the latter being reliably disposed in vertical slot in lock barrel 13 and having its lower end reduced to provide 25 a shoulder engaging a suitable seat in the slot to limit downward movement of the stem. Beyond the shoulder portions, however, the stem presents a projection 42, penetrating the upper portion of the key 30 slot 18 and normally disposed in the path of the key so as to be elevated by the insertion of the latter whereupon the dial catch will be rocked on its pivot to disengage the teeth of the dial ring, which may 35 then be turned and set to indicate the hour of the next collection.

The head 14 of the lock barrel may have a pointer painted or otherwise provided thereon, as is shown at 43, and a large letter "M" arranged on the right hand side of the pointer, as seen in Figure 2. On the left hand side adjacent the letter "M" is an opening 44 behind which is formed a circular recess 45 in which is mounted for 45 rotation a small indicator 46 having thereon the letters "A" and "P". Integral with this dial is a pinion 47 arranged to mesh with the teeth 34' of the dial ring 17. The ratio being such that dial 46 will be rotated to 50 alternately present the letters "A" and "P" in line with the opening 44 as the hour 12 is successively brought opposite pointer 43, thereby automatically indicating day or night, that is, A. M. and P. M. collections.

55 In practice, when the key is inserted in the lock to unfasten the door, the dial ring of the collection indicator is automatically released, and hence, may be conveniently

adjusted to indicate the time of the next 60 collection; the ring making one complete revolution every twelve hours. The lock mechanism is preferably of the key-actuated type and may be of any conventional and well known type most suitable for the purpose in view.

65 In practice, I have found that the form of my invention illustrated in the accompanying drawings and referred to in the above description, as the preferred embodiment, is the most efficient and practical; yet 70 realizing the conditions concurrent with the adoption of my device will necessarily vary, I desire to emphasize that various minor changes in details of construction, proportion and arrangement of parts, may be resorted to within the scope of the appended claims without departing from or sacrificing 75 any of the principles of this invention.

Having thus described my invention, and 80 without enumerating variations and equivalents, what I desire protected by Letters Patent is as set forth in the following claims:

1. A combination lock and collection indicator for mail boxes comprising a lock mechanism and time indicating means associated with said lock mechanism and including a graduated rotatable dial, means normally holding said dial against rotation, said means being operable to release 90 the dial upon the insertion of a key in the lock, and means operated by the adjustment of the dial for automatically indicating A. M. and P. M. collections.

2. A combination lock and indicator for 95 mail boxes comprising a lock mechanism including a fixed head and a rotatable dial having time graduation thereon, said fixed head having a pointer for reading the said graduation and an opening bordered on one side with the letter M, a member disposed in the rear of the said opening and presenting the letters A and P for registration therewith, said member being operable by the turning of the said dial to present the said letters A and P alternately at the opening during successive periods of rotation of the dial, means associated with the said lock mechanism for holding the dial against rotation and means operable upon the insertion of a key in the lock for effecting release of the said dial.

100 EDW. L. BISHOP.
